UNITED STATES PATENT OFFICE.

LOUIS E. GILES, OF NEW YORK, N. Y., ASSIGNOR TO UNDERWOOD COMPUTING MACHINE COMPANY, OF NEW YORK, N. Y., A CORPORATION OF NEW YORK.

COMPUTING-MACHINE.

1,370,428.

Specification of Letters Patent. Patented Mar. 1, 1921.

Application filed October 18, 1919. Serial No. 331,585.

To all whom it may concern:

Be it known that I, LOUIS E. GILES, a citizen of the United States, residing in New York, in the county of New York and State 5 of New York, have invented certain new and useful Improvements in Computing-Machines, of which the following is a specification.

This invention relates to improvements in 10 computing machines, and especially to machines capable of effecting algebraic computations, that is, of adding positive and negative numbers irrespective of their relative magnitudes, and of indicating the correct result, whether positive or negative.

The invention is herein disclosed as an improvement on a computing machine of the Underwood-Hanson type, such as the one illustrated and described in the Patent, No. 20 1,278,812, granted September 10, 1918, to Hans Hanson, but is adapted for use in connection with any computing machine having a register or totalizer comprising movable number wheels or other figure-carrying 25 elements, and means for effecting either addition or subtraction by varying the positions of said figure-carrying elements.

In the form in which the invention is 30 herein disclosed, the end sought to be attained is accomplished in a very simple and practicable manner by providing a duplicate set of figure-bearing elements or number wheels, corresponding in number and relative arrangement with the number 35 wheels of the totalizer, each wheel of the set being connected, by means of an idler, with the corresponding totalizer number wheel, and by providing for the added set of number wheels indexing means, herein 40 disclosed as a double-width sight-opening, for concomitantly directing attention to two or more rows of the figures thereon. The number wheels of the added set are so geared or connected to those of the totalizer and 45 the sight-openings are so disposed relatively to said wheels that whenever a "0" appears at the sight-opening of the totalizer, a "0" and a "9" will appear at the sight-opening of the added set of wheels. With such a 50 device, as will hereinafter be explained, the figures on one set of number wheels may be used to exhibit positive results accumulated in the totalizer, and those on the other set to exhibit negative results.

55 From the foregoing brief description, it

will be seen that the desired end is attained without the use of special carrying mechanism, mechanically-operated shutters, or other complicated mechanism, thus providing a very simple and practical device which 60 will be inexpensive to produce, and not likely to get out of order and disable the machine, or cause it to give erroneous results.

Other features and advantages will hereinafter appear.

65 In the accompanying drawings,

Figure 1 is a top view of the front portion of a computing machine of the Underwood-Hanson type, showing the novel relations between the figures on the number 70 wheels and the indexing means or sight-openings in accordance with one embodiment of my invention.

Fig. 2 is a section through the front portion of the machine, including an end view 75 of the usual totalizer, the added set of number wheels, and the idlers by which the wheels of the added set are geared to the corresponding totalizer number wheels. In this view, the figures on the number wheels 80 are diagrammatic, and are intended merely to show the relative positions of the figures on the peripheries with respect to each other and to their respective sight-openings.

Figs. 3, 4 and 5 are views of the exposed 85 portions of the number wheels and their indexing means or sight-openings, illustrating different relative positions assumed by the number wheels to indicate various totalizer readings.

90 As herein disclosed, the reference character 20 (Figs. 1 and 2) represents the front part of the casing of an Underwood-Hanson combined typewriting and computing machine, including the usual sight-opening 21, through which readings may be taken from the usual totalizer 22, comprising the usual 95 number wheels 23 and rack-bars 24. The usual tens-carrying mechanism for the totalizer and the mechanism for advancing the 100 racks-bars, so as to operate the number wheels are fully disclosed in the aforesaid Hanson patent, and the machine therein illustrated and described is in common use. The disclosure of the computing mechanism need 105 not therefore be set forth in detail herein.

Geared to each of the number wheels 23, by means of an idler 25, is a corresponding number wheel 26, of a secondary or subsidiary set of number wheels 27, the connec- 110

then between said number wheels being such that each number wheel of the subsidiary set will always rotate concomitantly with, and in exact accordance with, the corresponding number wheel of the totalizer 22. The subsidiary number wheels rotate in the same direction as those of the totalizer, and each is provided, at its periphery, with a "0" and the digits "1" to "9" as usual, but the digits on the subsidiary number wheels are arranged in inverse order, as indicated grammatically in Fig. 2, by the figures applied conventionally to the sides of said wheels.

26 27. It means for directing attention to, or reading, the figures on the number wheels 26 of the subsidiary set 27, from which readings are to be taken in a manner hereinafter more fully explained, there is provided in the casing 20 a sight-opening 28 of such width as to expose two adjacent rows of figures on the number wheels 26 instead of one row, as is usual on such machines.

28 29. When using a machine with my improvement applied thereto for ordinary arithmetical addition and subtraction, in which case the results are always positive, the readings may invariably be taken from the totalizer 30 number wheels, through the narrow sight-opening 21, as usual. But, should the machine be called upon to effect an algebraic computation, that is, if at any time the aggregate of the negative quantities added exceeds the aggregate of the positive quantities, so as to result in an overdraft, or to cause the machine to pass through "0", then the readings must be taken from the subsidiary number wheels, through the wide 35 sight-opening 28, and will be read partly from one row of figures and partly from the other, in a manner hereinafter explained by illustrative examples.

36 37. When the machine has been cleared, in 40 readiness to commence a series of computations, the usual totalizer number wheels will exhibit a row of "0"’s at the narrow sight-opening 21, and the subsidiary number wheels will exhibit a row of "0"’s and a 45 row of "9"’s at the wide sight-opening 28, as illustrated in Fig. 1. Starting with the machine in this condition, let it be assumed that the number 3,120,700 is to be added to the number 876,421, and that the number 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 from that previously accumulated in the totalizer, the correct algebraic sum, which should be -861,974, would not appear in the row of figures exposed at the upper sight-opening as before, but, instead of this result, there would appear, as indicated in Fig. 4, a complementary series of figures 999,138,026, which, if added to the correct result, ignoring the minus sign, would be represented by a "1" followed by as many "0"’s as there are denominational orders or decimal places in the totalizer. It is well known to those skilled in the art that this will happen whenever the number to be added is larger than that previously accumulated in the totalizer and of opposite character, as when a negative number is added to a smaller positive number.

It may be observed that the first figure at the upper sight-opening, after the last-mentioned algebraic computation has been effected (see Fig. 4), is a "9" instead of the usual "0", and this will always be true when a negative number has been added to a smaller positive number previously accumulated in the totalizer, provided the machine is not used to add or subtract numbers having as many digits as there are number wheels in the totalizer. In using a machine with my invention applied thereto, I therefore arbitrarily select one having at least one more number wheel in its totalizer than the number of digits of the largest number which it is intended to be capable of adding or subtracting, and assign the highest number wheel to a special purpose, that is, for use as a signal or warning, to indicate whether the result is positive or negative. Under such circumstances the highest number wheel of the totalizer will normally expose a "0" at the narrow sight-opening 21. This "0" can never be changed to "9" by adding positive numbers, except as a result of a large number of successive computing operations, and in no event could it be changed from "0" to "9" by adding positive numbers, except by being first caused to exhibit all of the digits "1", "2", "3", etc., in succession up to "9". It is well known, however, that the highest number wheel will be invariably caused to immediately expose a "9" whenever any negative number is added to a smaller positive number previously accumulated in the totalizer, so as to result in an overdraft and cause the machine to pass through "0". The appearance of the "9" on the highest number wheel at the upper or narrow sight-opening 21 may, therefore, serve as a warning or signal to the operative that the result indicated by the totalizer is negative, in which case the correct reading may be taken from figures exposed by the subsidiary number wheels at the lower or wide sight-opening 28, said reading being taken partly from the lower 120 sight-opening 28, as indicated in Fig. 3.

Should the machine now be operated in an attempt to subtract the number 2,109,314

row and partly from the upper row, as indicated by the figures inclosed in broken lines at 30 and 31 (Fig. 4).

Referring again to Fig. 4, it may be observed that the last figure in the upper row of figures, exposed by the wide sight-opening, is a significant figure, that is, a digit other than "0". Whenever this is the case, the negative quantity is read wholly from the lower row of figures, as at 30 (Fig. 4), except that the figure of lowest or units denominational order is read from the upper row, as indicated in broken lines at 31.

Should the machine now be operated in an attempt to add to the sum already accumulated in the totalizer another negative quantity, as, for example, -4,836,026, the correct result, -5,698,000, will again be found, as indicated in Fig. 5, partly in the lower row of figures and partly in the upper row, that is, the first three figures, 569, will be found in the lower row, as indicated in broken lines at 32, and the last four figures, 8000, will be found in the upper row, as indicated in broken lines at 33. It may be observed that the figures read from the upper row include but one significant figure followed by a series of "0"’s, and this will be found to be invariably the case. The last significant figure of a negative result will always be the last significant figure of the upper row of figures exposed at the lower or wide sight-opening 28, and the other significant figures will be found in the lower row. A negative result may therefore be read directly from the figures of the subsidiary number wheels exposed at the wide sight-opening by merely remembering that all except the last significant figure must be taken from the lower row and the last significant figure from the upper row.

The reading is always negative and must be taken in the above-described manner whenever the "9" of the number wheel of the highest denominational order is exposed at the upper or narrow sight-opening. Whenever the number wheel of highest denominational order of the totalizer exposes a "0" at the upper or narrow sight-opening, the result is positive and is to be read directly from the single row of figures at that sight-opening in the usual manner.

The above-stated rule is simple and invariable in its application, and could be readily mastered by an operative in a negligible space of time, after which the negative readings may be taken from the machine with the same degree of ease and accuracy as in reading the positive results in an ordinary totalizer.

It will be obvious that the double-width sight-opening may be used in connection with either set of number wheels, and that either set of figures may be used to exhibit

positive results, the other being used to exhibit negative results.

If desired, the figures on the subsidiary number wheels may be differentiated from those of the totalizer itself, as by making those of the totalizer black, to indicate positive results, and those of the subsidiary set red, to indicate negative results. This, however, is in no manner necessary, since the difference in location and width of the sight-openings may be relied upon as a means for determining from which number wheels results of either character are to be taken.

Any appropriate means may be substituted for the idlers for causing corresponding wheels of the two sets to be concomitantly rotated. In the form herein disclosed, the number wheels of the respective sets rotate in the same direction, and the figures on one set are duplicates of those on the other, except that they are arranged in inverse increasing order of magnitude, that is, rotation, such as to expose figures on one wheel in increasing order of magnitude, causes those of the other to be exposed in decreasing order of magnitude. Should the wheels be so geared or connected as to rotate in opposite directions, the figures should be applied to the number wheels in the same relative order, so as to be brought to the sight-openings in the inverse order explained above.

Variations may be resorted to within the scope of the invention, and portions of the improvements may be used without others.

Having thus described my invention, I claim:

1. In an algebraic computing machine, in combination, a set of number wheels having figures by which positive results may be represented, a second set of number wheels having figures by which negative results may be represented, means for causing each wheel of the second set to rotate concomitantly with the corresponding wheel of the first set, indexing means for directing attention to one row of figures on the wheels of one of said sets from which a reading of one character may be taken, and indexing means for concomitantly directing attention to two rows of the figures on the wheels of the other set, from which a reading of the opposite character may be taken, partly from the figures of one row and partly from the figures of the other.

2. In an algebraic computing machine, in combination, a set of number wheels having figures by which positive results may be represented, indexing means for directing attention to one row of said figures from which a reading may be taken, a second set of number wheels having figures from which a negative result may be taken, means for causing each wheel of the second set to ro-

tate concomitantly with a corresponding wheel of the first set, and indexing means for concomitantly directing attention to two rows of the figures on the wheels of the second set, from which a reading may be taken, partly from the figures of one row and partly from those of the other.

3. In an algebraic computing machine, in combination, a set of number wheels having figures by which positive results may be represented, a second set of number wheels having figures by which negative results may be represented, means for causing each wheel of the second set to rotate concomitantly with the corresponding wheel of the first set, and an index for said wheels having sight-openings for exposing one row only of the figures on the wheels of one of said sets, and for concomitantly exposing two rows of the figures on the wheels of the other of said sets.

4. In a computing machine, in combination, a set of number wheels having figures by which positive results may be represented, an index for said wheels having a sight-opening for exposing one row only of the figures thereon, a second set of number wheels having figures by which negative results may be represented, means for causing each wheel of the second set to rotate concomitantly with the corresponding wheel of the first set, and an index for the wheels of said second set having a sight-opening for concomitantly exposing two rows of the figures thereon.

5. In an algebraic computing machine, in combination, a set of number wheels, each having figures thereon including a "0" and the digits "1" to "9", a second set of number wheels, each having figures thereon including a "0" and the digits "1" to "9", means for causing each wheel of the second set to be rotated concomitantly with a corresponding wheel of the first set, and indexing means for concomitantly directing attention to one row of the figures on one of said sets and to two rows of the figures on the other of said sets, the relative positions of the figures on the two sets of number wheels being so related to each other and to the positions of the indexing means that an indexed digit of a wheel of one set when added first to one and then to the other of the two indexed digits of the corresponding wheel of the other set will add "9" and "10", respectively.

6. In an algebraic computing machine, in combination, a set of number wheels, each having figures thereon comprising a "0" and the digits "1" to "9", a second set of

number wheels, each having figures thereon including a "0" and the digits "1" to "9", means for causing each wheel of the second set to rotate concomitantly with the corresponding wheel of the first set, and indexing means for concomitantly directing attention to one row of the figures on the wheels of one set and to two rows of the figures on the wheels of the other set, the connection between corresponding wheels of the two sets being such as to cause them to rotate in the same direction, the figures being applied to said wheels in an inverse order, so that rotation such as to cause the digits of one wheel to be brought to the indexing position in an increasing order of magnitude will concomitantly cause the digits on the corresponding wheel of the other set to be brought to the indexing position in a decreasing order of magnitude.

7. In a computing machine, in combination, a totalizer having two sets of number-wheels, each having figures comprising a "0" and the digits "1" to "9", and means for concomitantly indexing one row of figures of the wheels of one of said sets and two rows of figures of the wheels of the other of said sets.

8. In a computing machine, in combination, a totalizer having two sets of number-wheels, each having figures comprising a "0" and the digits "1" to "9", and an index having two sight-openings for concomitantly exposing one row only of the figures on the wheels of one of said sets and two rows of the figures on the wheels of the other of said sets.

9. In an algebraic totalizer, in combination, a series of devices arranged side by side, having "0" and the digits "1" to "9", inclusive, positioned at regular intervals in an endless path thereon, a second series of devices having thereon digital indications similar to those of the first series, means whereby digital changes of value on the devices of one series will be reverse with respect to corresponding changes of value on the devices of the other series, and indexing means directing attention to a single row of digits on the devices of one of said series, and to two rows on the devices of the other of said series, one of the last-mentioned rows showing digits complementary to the base "9" and the other showing digits complementary to the base "10", of the digits in the single row.
